UNITED STATES PATENT OFFICE.

RAY W. LYON, OF TRAIL, OREGON.

BEATER AND MIXER.

Application filed April 30, 1924. Serial No. 710,039.

To all whom it may concern:

Be it known that I, RAY W. LYON, a citizen of the United States, residing at Trail, in the county of Jackson and State of Oregon, have invented certain new and useful Improvements in a Beater and Mixer, of which the following is a specification.

My invention relates to improvements in beating and mixing devices commonly used 10 for beating eggs, cream or other household commodities.

An important object of the invention is to provide a beating and mixing device which may be firmly secured to a table or the 15 like, and easily operated.

A further object of the invention is to provide a device of this character whereby the beater and mixer element may be raised or lowered as desired.

20 A still further object of the invention is to provide a device of this character which is comparatively simple in construction, durable, and efficient for the purpose intended.

25 In the accompanying drawing forming a part of this specification and in which like numerals are employed to designate like parts throughout the same:

Figure 1 is a side elevation of my improved device shown mounted upon the edge 30 of a table.

Figure 2 is a top plan view of the device embodying my invention, and

Figure 3 is an end elevation of the same.

In the drawing, wherein for the purpose of illustration is shown the preferred embodiment of my invention, the numeral 5 generally denotes a table, shelf or other suitable resting place. By the numeral 6 I denote a common form of bowl employed while beating or mixing commodities. Referring more particularly to my invention 7 indicates the upright supporting bracket which is substantially triangular in form and is 45 provided with a reinforcing web 8 formed on the central portion thereof. The lower extremity of the bracket 7 is provided with an extension flange 9 which rests upon the table and is retained in position by means of 50 an angular bracket 10 formed on the lower portion of the upright support 7 and having an internally threaded opening formed in the lower portion. A threaded thumb screw 11 is mounted within the threaded opening and is provided with a swivel cap 12 mounted 55 upon the upper extremity of the thumb

screw 11 for the purpose of engaging the underside of the table or supporting means.

A horizontal arm 13 is formed on the upper extremity of the supporting bracket 7. 60 This bracket is preferably composed of an angular bent plate having a vertical extension 14 bent at the upper extremity to form a semi-circular flange 15.

A vertical rod 16 is rotatably mounted 65 through suitable openings formed in the bracket 13 and carries a collar 17 rigidly secured to the rod by means of a set screw and limits the downward movement of the rod 16. Rotatably secured to the upper 70 extremity of the rod 16 is a handle member 18 connecting with a sleeve 19 rigidly secured to the rotatable rod. The rod 16 is circular in cross section, the upper extremity having a flat side as at 20 adapted to engage 75 an appropriate opening formed in a toothed gear 21 mounted upon the rod 16 and preferably provided with an extension hub 22. The toothed gear 21 is driven by a crown gear 23, mounted upon the side of the 80 bracket 13 by means of a rivet or the like and meshing with the gear 21, the crown gear being rotated by means of a handle 24 mounted upon the outer periphery thereof. 85

As it is desirable to raise and lower the 90 rod 16 without like movement of the gear 21 this gear is prevented from vertical movement by means of a clip 25 formed upon the bracket 13 and bent about the gear 21 to prevent raising of the same. In order 95 that the gears 21 and 23 may efficiently mesh the bracket 13 has a longitudinal slot 26 formed therein to permit the gear 21 to extend outwardly and engage the crown gear 23.

The agitating means comprise a pair of strips or vanes 27 substantially circular in formation at the lower extremities and provided with angular extensions 28 at the upper portion, the upper extremity being provided with openings to receive the rod 16 which is inserted through the vanes 27 at the upper and lower extremities and firmly secured thereon by means of nuts or the like. I do not wish to limit my invention to this 100 particular construction of beating or agitating means, the particular construction shown employing what is commonly known as a single beater while I contemplate the use of double beaters and numerous other 105 agitating means commonly employed.

In use, my device may be readily mounted

upon a table, shelf or any convenient support, the agitators being raised by means of the handle 18 and the bowl containing the commodities to be beaten or mixed positioned below the same. The handle is then lowered causing the beater to be inserted within the commodity and the handle 24 actuated causing rotation of the crown gear 23 which in turn meshes with the gear 21 causing rotation of the shaft 16 and beaters. It is also obvious that the shaft may be raised and lowered while the beaters are being rotated thus more efficiently beating and mixing the commodity within the bowl.

It is to be understood that the form of my invention herewith shown and described is to be taken as the preferred example of the same, and that various changes as to the shape, size and arrangement of parts may be resorted to without departing from the spirit of the invention, or the scope of the subjoined claim.

Having thus described my invention, I claim:

A beater and mixer comprising a bracket 25 having a plate portion provided at its end with angularly disposed flanges one of which is provided with an inwardly disposed lip, the plate portion being provided at a point opposite the said lip with an opening, a gear wheel journaled upon one end portion of the plate and having one side portion disposed under the lip and its opposite side portion passing through said opening, a shaft slidably mounted through the angularly disposed end flanges of the plate portion and adapted to rotate with the gear wheel, means mounted upon the plate portion for rotating said gear wheel, beater members carried by the shaft, a handle having a substantially elliptical head, and a sleeve mounted at the side of the head of the handle at a point between the ends thereof, said sleeve being loosely connected with the shaft.

In testimony whereof, I have affixed my signature.

RAY W. LYON.
